Patented Oct. 5, 1926.

UNITED STATES PATENT OFFICE.

ROBERT T. SUDDENDORF, OF CINCINNATI, OHIO, ASSIGNOR TO THE WITT CORNICE COMPANY, OF CINCINNATI, OHIO.

WASTE RECEPTACLE.

Application filed January 7, 1926. Serial No. 79,843.

This invention relates to improvements in waste receptacles, one object of the invention being to provide fireproof receptacles which shall be adapted particularly for the reception of oily waste such as employed for use about machinery, and to so connect the cover with the body portion of the receptacle that closure of the latter will be insured at all times except when waste is being deposited thereinto or discharged therefrom.

A further object is to provide simple and efficient operating mechanism for the cover, which mechanism shall be permanent- 15 ly associated therewith and with the body of the receptacle; by means of which, the cover may be readily raised by the application of foot power, and which mechanism will permit the cover automatically 20 to close down on the body of the receptacle upon removal of the power which served to raise the cover.

With these and other objects in view, the invention consists in certain novel features 25 of construction and combinations of parts as hereinafter set forth and pointed out in the claims.

In the accompanying drawings,—

Figure 1 is a vertical sectional view of 30 a covered receptacle showing an embodiment of my improvements.

Figure 2 is a plan view, and

Figure 3 is a horizontal sectional view.

The body 1 of the receptacle will prefer- 35 ably be made of sheet metal and its upper edge portion will preferably be reinforced by a band 2. The lower edge portion of the receptacle body may be made to project below the bottom 3 and this projecting or 40 flange-portion 4 is reinforced by means of a band or metal strap 5. To the reinforced bottom portion of the receptacle body, supporting legs 6 are permanently secured and braces 7 connect said legs, said braces and 45 legs thus forming a supporting frame which is secured permanently to the lower portion of the receptacle body. Ears 8 are secured to diametrically opposite portions of the receptacle body, for the accommodation of 50 a bail or handle 9.

The cover 10 for the receptacle may be made of sheet metal and provided with a peripheral flange 11 to overhang the upper edge of the body 1 and said cover may be 55 provided with a hand-hold 12. A bracket

13 having outwardly projecting parallel arms 14 is secured permanently to the reinforced upper edge portion of the body 1 and to these arms, ears 15 on a plate 16 are hingedly connected. The plate 16 is shaped 60 to conform to the cover 10 and is secured to the latter, the ears 15 being formed by bending the side portions of said plate outwardly. The plate 16 extends from the edge portion of the cover an appreciable distance 65 toward the center of the latter and at the inner end of this plate, a bracket 17 is provided. This bracket may be integral with the plate 16 or it may be made separate therefrom and secured to the cover. The 70 bracket 17 provides parallel ears, between which the upper inwardly projecting end 18 of a rod or pitman 19 enters and to which said inwardly projecting portion of the rod or pitman is pivotally connected by 75 means of a pin 20 passing through the same and through the bracket ears on the cover. A bail lever 21 encircles the lower portion 80 of the receptacle and is pivotally connected at diametrically opposite points, as at 22, to the reinforced lower portion of the receptacle body. The lower end portion of the rod or pitman 19 is pivotally connected with the rear portion of the bail lever 21 and the front portion of the latter is provided with 85 a foot piece 23.

It will be observed that the connection of the rod or pitman 19 with the cover is an appreciable distance inwardly from the edge 90 of the latter and that the construction is such that the normal tendency of the cover is to close by its own weight and therefore the use of springs or weights to insure the closing of the cover down on the receptacle body are obviated.

In order to prevent the bail or handle 9 from falling toward the hinged portion of the cover and the operating connections, lugs or ears 24 are secured to the flanged portion of the cover and serve as stops for 100 the bail or handle.

It is desirable that the opening throw of the cover shall be limited so that said cover may not be thrown back too far, thereby preventing it from dropping automatically 105 to closed position when the pedal lever is released. Stops are, therefore, provided to limit the upward movement of the cover and these stops may conveniently be formed by the downwardly projecting portions 15^a of 110

the ears 15, which latter are adapted to engage the upper portion of the cam body as indicated by dotted lines in Figure 1.

Having fully described my invention what 5 I claim as new and desire to secure by Letters Patent, is:

1. The combination with a receptacle body and a cover hinged thereto, of a foot lever member pivotally connected with the lower 10 portion of the receptacle body and a pitman pivotally connected at its lower end to said lever member and having its upper end overhanging the cover and pivotally connected with the cover an appreciable distance inwardly from the edge of said cover.
2. The combination with a receptacle body and a cover, of a plate secured to the cover and provided with parallel ears, a bracket secured to the body and having parallel 20 arms with which said ears are hingedly connected, an operating lever, and a connecting rod pivoted to said operating lever and passing between said ears and pivotally connected with the cover between the center 25 and edge of the latter.
3. The combination with a receptacle body and a cover hinged thereto, of a foot

lever pivotally connected with the receptacle body, a connecting rod pivotally attached to said foot lever and provided at its upper end 30 with an inwardly projecting portion normally disposed over the cover and terminating an appreciable distance from the edge of the cover, and a pivotal connection located between the center and edge of the 35 cover adjacent the hinged part of the latter, for the inwardly projecting portion of said connecting rod.

4. The combination of a receptacle body, outwardly projecting arms on the body at 40 the top thereof, a cover adapted to rest on the body, ears projecting from the cover and hinged to the arms on the body and extended downwardly beyond the arms to impinge against the body and limit the opening movement of the cover, a lever mounted on the body, and a pitman connected at its lower end to the lever and at its upper end to the cover at a point between the center and the edge thereof. 45

In testimony whereof, I have signed this specification.

ROBERT T. SUDDENDORF.
